UNITED STATES PATENT OFFICE.

WILLIAM B. KILGORE, OF CRAFTON, PENNSYLVANIA, ASSIGNOR OF ONE-HALF TO ERNEST O. C. KUHNEL, OF CRAFTON, PENNSYLVANIA.

PUNCHING-MACHINE.

No. 931,431.

Specification of Letters Patent.

Patented Aug. 17, 1909.

Application filed June 8, 1908. Serial No. 437,238.

To all whom it may concern:

Be it known that I, WILLIAM B. KILGORE, a citizen of the United States, residing at Crafton, in the county of Allegheny and 5 State of Pennsylvania, have invented certain new and useful Improvements in Punching-Machines, of which the following is a specification.

My invention relates to punching machines 10 and particularly to punching machines adapted to perforate plates, angles and similar metallic forms used in structural and allied arts.

The object of my invention is to provide 15 an accurate, facile and rapid means for accomplishing the perforation of blanks.

I accomplish these objects by a novel arrangement and combination of parts, herein-after described, reference being made to the 20 drawings forming part of this specification wherein:—

Figure 1 represents a vertical end view of my improved punching machine. Fig. 2 is 25 a plan view showing the correlation of the blank table to the templet table, with a punch, the greater part of the punch being removed for the sake of clearness. Fig. 3 is a detail in perspective of the operating arm by which the blank is moved and shows 30 also the controlling means for setting the punch. Fig. 4 is an end view of said arm and the electrical contacts, somewhat enlarged, and more clearly bringing out the detail thereof. Fig. 5 is a detail of the stock 35 and punch therein, showing the gag by which said punch is locked in the stock.

Referring again to the drawing for a detailed description of my invention, 1 represents a punch of any usual type provided 40 with a gear 2, a pinion 3, connecting with suitable belt pulleys 4 and fly wheel 5, by which power from any convenient source, may be applied to operate the punch. It will be understood that any other convenient 45 means of applying power may be substituted for the pulleys and gear. In the form shown and described, it is intended that the power be applied continuously to the machine, reciprocating the stock 6 and punch 7 uniformly, the punch 7 being loosely seated in the stock and free to recede thereinto when brought into contact with the blank except at such times as said punch 7 may be locked 50 in the stock 6 by a suitable gag 8.

55 A bed adapted to support and carry the

blank to be operated upon is formed by a frame 9 provided with wheels 10 adapted to move upon the rails 11—11 to allow for longitudinal movement of the said bed with the blank 12 carried thereupon. The rails 60 11—11 are connected by suitable cross-bars 13—13 to form a carriage provided with grooved rollers 14—14, mounted in suitable bearings 15 and adapted to engage the rails 16—16 to permit of transverse movement of 65 said carriage. By this arrangement of the blank carrying bed, longitudinally movable and superimposed upon the transversely movable carriage, it will be seen that I obtain a universal movement of the blank so 70 that any desired portion of the surface of said blank may be brought under the punch 7. Adjacent these coöperating carriages is located a templet table 17 fixed rigidly in position and adapted to support the templet 75 18, of wood or other suitable material, and provided with templet holes 19 corresponding in relative position with the perforations to be punched in the blank 12. The said templet is, in practice, clamped rigidly to 80 the templet table 17 and remains fixed relatively to the punch and does not have any movement whatsoever.

The blank-carrying bed is provided with a projecting arm 20 and suitable bracing 85 21, therefor, to rigidly connect the operating handle 22 with the said bed. By means of this handle 22 and connecting arm 20, the blank-carrying bed may be moved longitudinally and transversely to bring the blank 90 12 into position to receive the punch 7. It will be understood that the blank 12 is rigidly clamped to the bed by means of suitable clamps 23 and suitable supporting means 24 upon said bed. Suitable 95 bracing rods and bearings 25^a, 25^b, 25^c and 25^d strengthen the bed and carriage. Connecting with the arm 20 is an index pin 26, preferably tapered and supported somewhat to one side of the arm 20 by an extension 27 so as to be more apparent to the operator. This index pin is adapted to enter the templet holes 19 in the templet 18 when the arm 20 is guided by the operator, and when said index pin is brought opposite to 100 105 and inserted in the selected templet hole, the said blank 12 is positioned so that the punch 7 will make the perforation in the blank correspond with the said templet holes.

The index pin having been inserted in the templet hole, the operator clasps the handle 28 on the lever 29, fulcrumed at 30 and brings down the spring contact clip 31, attached to the opposite end of said lever 29, into engagement with the electrical terminals 32 and closes the circuit connecting therewith. This electrical circuit consists of the wires 33^a and 33^b connecting with the solenoid 34, any suitable supply of current being applied to said circuit, shown arbitrarily at 35. Connecting with said solenoid 34 and operated upon thereby is a rod 36 communicating by means of a rigid connection 37, a guide 38 being provided for said connecting rod 37. Any other convenient means of connection between the solenoid and the gag may be provided, for example:— a lever connection or the direct action of the solenoid upon the gag; but I have found the arrangement shown to be convenient as it places the solenoid out of possible interference with the blank.

The index pin having been seated in the selected templet hole and the circuit closed by means of the handle 28, as above described, the gag 8 operated upon by the solenoid 34 is thrown in and locks the punch 7, whereupon the next descent of the punch 7 perforates the plate or blank at the point corresponding in relative position to the templet hole of the templet. It will therefore be seen that the operator may, at will, successively punch the plate or other blank with any desired arrangement of perforations no matter how complex they may be, by the simple operation of moving the handle 22 until the index pin seats in the selected templet hole and, without changing the operator's grasp upon said handle 22, he may close the circuit and lock the punch as above described.

The spring 29 tends to hold the contact clip 31 out of connection with the circuit terminals when the handle 28 is not grasped by the operator. It will therefore be seen that the operator's entire attention may be given to the entering of the index pin in the templet hole and that no attention whatever need be given to the blank or the punch, the templet once having been set for the operation and the plate clamped upon its bed.

My improved apparatus is free from complications of gearing and the like so that there is no possibility of any inaccuracy in the position of the perforations punched in the blank and there can be no variation between the relative position of the templet holes and the perforations in the blank because of the direct and rigid connection of the index pin with the blank-carrying table.

The advantages of my improved apparatus will be apparent to those skilled in the art, and

Having thus fully described my invention, I claim as new and desire to protect by Letters Patent of the United States:—

1. In a punching machine, a fixed templet-support adapted to receive a templet, a work support movable both longitudinally and laterally, a tool coöperating therewith, an index-pin coöperating with said templet, means for moving said work support and index-pin in unison and a device for controlling the operation of the tool, carried by and movable with said means said device being operable independently of the said means. 70

2. In a punching machine, a fixed templet-support adapted to rigidly support a fixed templet, a work support movable longitudinally and laterally, a punch coöperating therewith, an index-pin coöperating with said templet, means for moving said work support and index-pin in unison, and a device 80 for controlling the operation of the punch carried by said means said device being operable independently of the said means.

3. In a punching machine, a fixed templet-support adapted to rigidly support a fixed templet, a work support movable both longitudinally and laterally, a punch coöperating therewith, an index-pin coöperating with said templet, a handle for moving said work support and index-pin in unison, and means 90 carried by the handle for controlling the operation of the punch said means being operable independently of the movement of the handle.

4. In a punching machine, a fixed templet-support adapted to receive a templet and maintain same in a fixed position, a work support movable longitudinally and laterally, a punch coöperating therewith, an index-pin coöperating with said fixed templet and rigidly connected with the work support, a handle for moving said work support and the attached index-pin, and an electric circuit having a magnet therein to 100 actuate the punch. 110

5. In a punching machine, a fixed templet-support adapted to receive a templet and maintain same in a fixed position, a work support movable longitudinally and laterally, a punch coöperating therewith, an index-pin coöperating with said fixed templet and rigidly connecting with the work support, a handle for moving said work support and the attached index-pin, an electric circuit having a magnet therein to actuate the 115 punch, and means attached to said handle to close and open said electric circuit. 120

6. In a punching machine, a fixed templet-support adapted to receive a templet and fixedly support same, a table movable longitudinally and laterally and adapted to receive a blank to be perforated, a reciprocable punch coöperating with said table and provided with a gag, an index-pin coöperating with the said templet and connecting with 125 130

said table, a handle for moving said table and index-pin in unison, an electric circuit having a magnet therein to actuate the gag of said punch, and means attached to said handle to close and open said electric circuit, substantially as described.

7. In a punching machine, a fixed templet-support adapted to receive a templet, a manually movable work-support movable both longitudinally and laterally, a tool co-operating therewith, means for manually moving said work-support, an index pin carried by said means and co-operating with the templet, and a device for controlling the operation of the tool, said device being carried by and movable with said means and operable independently thereof.

8. In a punching machine, a punch and operating means therefor, a work-support movable longitudinally and laterally in co-

operative relation to the punch and comprising a pair of fixed tracks, a carriage movable on said tracks, a pair of tracks on said carriage and movable therewith, and a work-supporting frame movably supported upon the tracks on said carriage; a fixed templet-support adapted to receive a templet, an index-pin co-operating with the templet, means for manually moving said index-pin and work-support in unison, and a device for controlling the operation of the tool carried by and movable with said means, said device being operable independently of the said means.

In testimony whereof I have affixed my signature in presence of two witnesses.

WILLIAM B. KILGORE.
